UNITED STATES PATENT OFFICE

2,688,420

TRAY AND BOX.

Ray H. Bishop, San Francisco, and Raymond F. Hoopes, Sr., Burlingame, Calif.

Application March 13, 1950, Serial No. 149,354

2 Claims. (Cl. 220—84)

1

This invention relates to trays and boxes. The primary object of the invention is to provide a tray or box for the handling of merchandise, particularly in bakeries for the delivery of bread, cake, doughnuts, cookies and the like bakery products, and which box is light, easy to handle and to stack and is sanitary.

The features of our invention are:

A light skeleton frame and a lining of fibreboard or the like held in the skeleton frame so as to be easily replaceable and thus combining lightness, durability and facility to keep the tray in sanitary condition; a light lining preferably of fibreboard which can be stored and shipped in collapsed flat position and which can be extended to fit into the frame of the tray so as to be prevented from collapsing while in use; a rim or top edge structure which has a limited resiliency and which provides a projection for engagement with the top edges of the sides of the lining or removable walls; integral elements on the skeleton frame to facilitate interlocking and stacking; easy adaptation for various uses and retaining the facility of replacing of the inserts.

We are aware that some changes may be made in the general arrangements and combinations of the several devices and parts, as well as in the details of the construction thereof without departing from the scope of the present invention as set forth in the following specification, and as defined in the following claims; hence we do not limit our invention to the exact arrangements and combinations of the said device and parts as described in the said specification, nor do we confine ourselves to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

Fig. 1 is a perspective view of the skeleton frame of the tray constructed in accordance with our invention.

Fig. 2 is a fragmental sectional view of the tray with the insert therein.

Fig. 3 is a sectional detail view showing the cross sectional shape of a bar of the skeleton frame, the section being taken on the lines 3—3 of Fig. 1.

Fig. 4 is a perspective view of the insert for the skeleton frame in unfolded position.

Fig. 5 is a fragmental sectional view of a pair 55

of adjacent superimposed trays as they may be placed in stacked position.

Fig. 6 is a fragmental bottom plan view of a corner of the tray showing a stacking projection.

Fig. 7 is a fragmental sectional view of the stacking projection of Fig. 6.

Fig. 8 is a fragmental sectional view of the tray viewing a corner thereof.

In carrying out our invention we make use of a skeleton frame 1 and a light and disposable insert 2.

The skeleton frame, in the form illustrated in Fig. 1, is particularly adapted for use as a bread box, and it includes horizontal bottom pieces 3. Each bottom piece 3 is of substantially angle construction so as to provide a bottom flange 4 and an upright side flange 6. These bottom pieces are suitably secured, preferably by spot welding, to the lower ends of vertical corner bars 7. Each 20 of these corner bars 7 is preferably of angle cross section. At each corner of the rectangular area defined by the bottom pieces 3 are provided suitable gusset plates 8 to reinforce the bottom structure. At least one cross bar 9 extends between opposite bottom pieces 3 for stiffening the bottom structure and for limiting the bending of the bottom of the insert 2 under the weight of the bread or the like therein.

The top section of the skeleton frame 1 includes a strip of suitable sheet metal which is wrapped around a wire or rod 11, which latter is formed into a rectangular shape parallel with the rectangular shape defined by the bottom pieces 3. The strip of sheet metal thus forms a tubular wrapping 12 around said wire 11, and it also forms a skirt 13 which extends downwardly from said tubular wrapping 12 and is preferably spot welded to the top portions of the vertical corner bars 7. The rim thus formed by the tubular wrapping 12 and the wire 11 overhangs or overlaps inwardly of the basket to form a ledge 14 projecting over and above the bottom flanges 4 of the respective bottom pieces 3. The insert 2 is pressed under said ledge 14 and is maintained in its upright position.

At each end of the cross bar 9 extends upwardly a vertical brace 16 between the upright flange 6 and the skirt 13.

The skirt 13 at the middle of each end of the tray is folded under inwardly so as to form a rounded grip 17 for the handling of the tray. At each end of the grip 17 is a vertical thumb brace 18 between the respective upright flanges 6 and portion of the skirt 13.

The cross bar 9, the brace 16 and thumb braces

18 are formed of the cross section shown in Fig. 3, namely are dished so as to form a rib 19 outwardly of the tray thereby to increase the rigidity of the brace.

The insert 2 is preferably made of fibreboard. It includes a bottom 21. At the longitudinal edges 22 of the bottom are side flaps 23 which are foldable up into the position shown in Fig. 4. At each end edge 24 of the insert bottom 21 is an end flap 26 which is foldable up into the upright position between the ends of the side flaps 23. Each end flap 26 is cut away at the middle of its top edge to form a grip recess 27 which is located opposite the grip 17 at the end of the tray 1. The insert is stored in a flat position, namely the end flaps 26 are folded over the bottom 21 and then the side flaps 23 are folded inwardly. This folded flap is placed into the tray so that the insert 21 rests upon the bottom flanges 4. Then the side flaps 23 and end flaps 26 are unfolded and pressed under the respective ledges 14 to be held in place. The height of the side flaps 23 and end flaps 26 is such that they fit tightly or snugly between the bottom flange 4 and the adjacent ledge 14. Thus the ledge 14 effectively holds the insert 2 in place when an empty tray is turned upside down, or when in handling a full tray upward pressure is applied to the bottom 4.

For facilitating stacking of the trays, we illustrate in Figs. 1, 5, 6 and 7 the use of generally triangular corner projections 28 at each corner of the tray 1. These projections are formed by a generally triangular hollow boss with outwardly extended flanges 29 at each edge thereof which latter are welded to the underside of the bottom flanges 4 at each corner of the tray. The triangular corner projections 28 are so arranged that the right angle sides thereof are spaced inwardly from and parallel with the adjacent sides at the corner of the tray so that when a tray is superimposed upon another, then the corner projections 28 fit into the corners of the top section of the lower tray and prevent the accidental sliding of one tray off the other.

Another form of stacking projection is illustrated in Fig. 2 and is in the form of ribs 31 pressed downwardly out of the bottom flanges 4 all around the tray 1.

We claim:

1. A tray of the character described comprising a base frame, generally vertical corner post members extended from the base frame, a top frame on the tops of said vertical corner post members, a disposable lining fitting into the area

defined by said frames, and a generally cylindrical solid rim element on said top frame projecting inwardly of the tray and above the adjacent edges of the lining, said lining including a bottom and sides foldable from a collapsed position over said bottom to an upright position between said base frame and said rim, the spacing between the base frame and said rim being such as to snugly receive said sides of the lining therebetween so as to hold said sides in upright position.

2. A tray of the character described comprising a base frame, generally vertical corner post members extended from the base frame, a top frame on the tops of said vertical corner post members, a disposable lining fitting into the area defined by said frames, and a continuous retaining rim element all around said top frame, said lining including a bottom and sides foldable from a collapsed position over said bottom to an upright position between said base frame and said rim element, said rim element extending inwardly of said tray overlying the top edges of said lining sides and being spaced from said base frame to such an extent as to snugly receive said lining sides therebetween so as to hold said lining sides in upright position, the lining sides at two opposite sides of the tray having handle recesses at their tops, and upright handle braces between the bottom frame and the top frame adjacent each side of said recesses spaced to serve as thumb rests.
